UNITED STATES PATENT OFFICE.

REUBEN J. EDWARDS, OF WATERBURY, VERMONT.

SCYTHE-SNATHE FASTENING.

1,360,351.

Specification of Letters Patent. Patented Mar. 26, 1913.

Application filed December 12, 1913. Serial No. 806,211.

To all whom it may concern:

Be it known that I, REUBEN J. EDWARDS, a citizen of the United States, residing at Waterbury, in the county of Washington and State of Vermont, have invented a new and useful Improvement in Scythe-Snath Fastenings, of which the following description, taken in connection with the accompanying drawings, is a specification.

10 My invention relates to that class of fastenings in which the tang, or bent portion, of the scythe blade engages a plate, pivoted to the snathe, by the adjustment of which plate the point of the scythe is thrown in or 15 out to meet the requirements of the user. In devices of this character, great difficulty has been experienced in perfecting a fastening which is capable of easy adjustment, without sacrificing strength and rigidity of 20 the structure after the adjustment has been made, and it is the object of this invention to overcome this difficulty.

A further object is to provide an adjustable fastening in which the fastening bolt 25 is of ordinary standard formation, thus doing away with bolts having specially constructed heads. A further object is to so construct the pivoted plate that the means for effecting its adjustment are plainly visible, whereby an exact adjustment is readily secured.

Further objects and advantages will appear from the following description of the invention taken in connection with the accompanying drawings, in which—

Figure 1 is a perspective view of the under side of the butt end of a scythe snathe having my invention applied thereto.

Fig. 2 is a longitudinal sectional view.
40 Fig. 3 is a perspective view of the adjusting plate.

Fig. 4 is a perspective view of the holding plate, which lies under the end of the adjusting plate and engages the latter to prevent it from swinging.

The same reference characters designate the same parts in all the figures.

1 designates a heel ring or band, which encircles the butt end of the snathe 2. The band 1 is provided with an outstanding lug 1', against which abuts the rear edge of the tang A, as shown by the dotted lines, Fig. 1. Passing through the band 1 and snathe 2 is the stem 3 of a loop bolt 4, the loop of 55 which encircles and holds the blade tang A. The band 1 is provided with an extension

5 on one side, to provide a bearing 6 for a stud 7, which is integral with an adjustable plate 8, and provides a pivot about which said plate may be oscillated. The plate 8 is 60 provided with a pair of similar apertures 9, 9, into one or the other of which the bent end A' of the tang projects. Beyond the apertures 9, 9, and near the outer end, the plate is provided with a curved transverse 65 slot 10, which loosely receives a clamping bolt 11.

In order to provide for a graduated adjustment of the plate 8, and in order to provide means by which it may be firmly held 70 in any adjusted position, the said plate is gradually diminished in thickness along its edge farthest removed from the pivot point, and in the beveled portion thus formed are provided a number of radially disposed 75 teeth 12 formed with their active operating portions on the face of the plate adjacent the snathe, but plainly visible on the opposite face of the plate in the form of notches in the edge thereof, by reason of being 80 formed in the said beveled portion, as clearly seen in Fig. 1.

Firmly embedded in the snathe, and secured against movement therein by means of a projection 13 thereof pressed into the 85 wood, is a holding plate 14, provided with an aperture 15 for the passage of the bolt 11, and having a lug 16 thereon, in the face of which are cut a pair of teeth 17 so proportioned and beveled as to coact with the 90 teeth 12 of the plate 8. The teeth 12, at their inner portions, project outward slightly from the face of the plate 8, and the opposed face of the holding plate 14 is accordingly provided with a curved transverse groove 18 95 adapted to receive said projecting portions.

On the opposite side of its slot 10, the plate 8 is provided with additional teeth 19, each depression therebetween being in radial alinement with one of the teeth 12, and on 100 the holding plate 14 there is provided adjacent the inner edge of the aperture 15, a single centrally disposed tooth 20, in radial alinement with the depression between the two teeth 17, which tooth 20 is adapted to 105 enter the depressions between the teeth 19, to provide additional means, acting in conjunction with the teeth 12 and 17, for preventing relative movement between the plates 8 and 14, when the latter are drawn 110 into close contact by the tightening of a nut on the end of bolt 11. The said bolt, which

is of ordinary form, passes through both plates and also through the body of the snathe, as clearly seen in Fig. 2, and at its end is provided with a suitable washer 2', between the face of the snathe and the nut.

As is readily apparent, the construction above described, provides interengaging teeth on the contacting faces of the superposed relatively movable plates, which teeth, by reason of being cut in portions of said plates which are inclined with respect to said contacting faces, are plainly visible on the outside face of the uppermost plate, whereby a predetermined adjustment of the plates is readily secured. Furthermore, the structure is not thereby weakened, as would be the case if the teeth were formed in the edges, rather than in the contacting faces, of the plates.

I claim,

1. In a scythe snathe fastening, a socket plate pivoted at one end, and having a beveled edge at its free end, a stationary plate below said socket plate, having a portion thereof extended beyond the free end of said socket plate, and providing a projection having an inclined face in matching relation to the beveled edge of said socket plate, said

beveled edge and said inclined face having coöperating teeth lying in the plane of said bevel, whereby a visible relative adjustment between said plates is afforded, and means for clamping said plates together.

2. In a scythe snathe fastening, a pivoted socket plate, having a beveled edge at its free end making an acute angle with the upper face of said plate, said edge having a series of teeth extending across the same in the plane of said bevel, from the upper to the under face of the plate, a stationary plate below said socket plate having a portion thereof extended beyond the free end of the socket plate and providing an upstanding projection having an inclined face contiguous to and in substantially the same plane as said beveled edge, said inclined face having a recess adapted to receive a tooth of said beveled edge, whereby a relative adjustment between said plates, visible from the upper face of said socket plate, is afforded, and means for clamping said plates together.

REUBEN J. EDWARDS.
